UNITED STATES PATENT OFFICE.

BENJAMIN F. TABER, OF BUFFALO, NEW YORK.

JOURNAL-BOX FOR ROTARY PUMPS.

SPECIFICATION forming part of Letters Patent No. 357,797, dated February 15, 1887.

Application filed January 11, 1886. Serial No. 185,155. (No model.)

To all whom it may concern:

Be it known that I, BENJAMIN F. TABER, of the city of Buffalo, in the county of Erie and State of New York, have invented new and 5 useful Improved Journal-Boxes for Rotary Pumps, of which the following is a specification.

This invention relates to an improvement in that class of rotary pumps which are provided 10 with a revolving piston-cylinder arranged eccentrically in an inclosing shell or case, the cylinder being provided with journals which revolve in suitable boxes formed on or secured to the sides of the shell or case. A pump of 15 this character is described and shown in Letters Patent of the United States No. 344,063, granted to me June 22, 1886, to which reference is here made.

The object of my present invention is to improve 20 the construction of the boxes in which the journals of the cylinder revolve, whereby these journals are kept sufficiently lubricated and prevented from running dry.

The invention consists, to that end, of the 25 improvements which will be hereinafter fully set forth, and pointed out in the claims.

In the accompanying drawings, Figure 1 is a longitudinal sectional elevation of a pump provided with my improvements. Fig. 2 is a 30 cross-section in line *x* *x*, Fig. 1, on an enlarged scale. Fig. 3 is a cross-section in line *y* *y*, Fig. 1, on an enlarged scale.

Like letters of reference refer to like parts in the several figures.

35 A represents the inclosing shell or case of the pump, which is supported on a suitable base-frame and provided with a suction-nozzle, *b*, and a discharge-nozzle, *c*, in the usual manner.

40 D represents the piston-cylinder, and E the pistons sliding in ways formed therein.

g represents the driving-shaft formed on one end of the cylinder *D*; and *h* is the stuffing-box formed in the adjacent head, *H*, of the 45 shell *A*, and inclosing the shaft *g*.

H' is the gland of the stuffing-box, secured thereto in any suitable manner and provided in its outer end with a screw-threaded collar, *i*, which receives an internally-threaded stuffing-nut, *I*. A suitable packing, *i'*, is interposed between the nut *I* and the collar *i*, to re-

tain on the journal the oil, which is introduced through an aperture, *h'*, from the oil-cup *J*.

j is a longitudinal groove formed on the inner surface of the gland *H'*, and extending nearly the length thereof and communicating with the aperture *h'*. The groove *j* forms a passage for the oil from the aperture *h'* lengthwise of the shaft *g*, whereby the portion of the 55 shaft which revolves in the gland *H'* is kept sufficiently lubricated.

K represents a journal formed on the opposite end of the cylinder *D*.

l is a stuffing-box formed on the adjacent 60 head *L* of the shell *A* and embracing the journal *K*.

M represents the gland of the stuffing-box *l*, constructed with a closed outer end, *m*, which covers the outer end of the journal *K*, whereby 70 the escape of the oil from the gland is prevented. The gland *M* is provided with an oil-aperture, *O*, which communicates with channels *S*, extending downwardly and partly around the journal *K*, and which have sufficient capacity to hold a suitable quantity of oil. The gland *M* is also provided with a longitudinal groove, *r*, which communicates with the aperture *O* and channels *S*. The groove *r* is formed on the inner surface of the 75 gland, and extends to nearly the inner end of the gland.

T is an oil-cup secured to the gland *M* and communicating with the aperture *O*, whereby the oil is supplied to the channels *S* and groove 80 *r*. As the journal *K* is the only support of the cylinder *D* at the end on which it is formed, it requires this extra protection against running dry, while the shaft *g*, which is supported in several bearings, is more easily kept properly lubricated. The gland *H'* is also provided with channels similar to the channels *S*, which communicate with the oil-aperture *h'* and extend downwardly and partly around the shaft *g*, to insure a more complete lubrication to the 95 shaft *g*. A suitable packing, *u*, is interposed between the stuffing-boxes and the journals and the inner ends of the glands, whereby the oil is retained on the journals.

I claim as my invention—

1. The combination, with an inclosing-shell, 100 *A*, and a piston-cylinder having a journal, *K*,

- of the stuffing-box *l* and the gland *M*, having its outer end closed, whereby the outer end of the journal is covered, substantially as set forth.
2. The combination, with an inclosing-shell, *A*, and a piston-cylinder having a journal, *K*, of the stuffing-box *l* and a gland, *M*, having its outer end closed and provided with oil-channels *S*, extending downwardly and partly around the journal, substantially as set forth.
3. The combination, with an inclosing-shell, *A*, and a piston-cylinder having journal *K*, of the stuffing-box *l* and a gland, *M*, having its outer end closed and provided with an aper-
- ture, *O*, channels *S*, and groove *r*, substantially as set forth.
4. The combination, with an inclosing-shell, *A*, and a piston-cylinder having a driving-shaft, *g*, of the stuffing-box *l*, the gland *H'*, provided with a threaded collar, *i*, and the stuffing-nut *I*, applied to said collar, substantially as set forth.

Witness my hand this 30th day of December, 1885.

BENJAMIN F. TABER.
